AUTOMATIC WINDING MACHINE

George A. Weimer, Cleveland, Ohio

Application June 8, 1937, Serial No. 147,067

5 Claims. (Cl. 242—18)

This invention relates to apparatus for automatically winding thread on bobbins or spools.

The primary object of the invention is to provide apparatus whereby bobbins or spools will have the thread wound thereon, broken at the completion of the winding operation upon a particular spool and automatically applying the thread to another spool or bobbin without manual operation thereby saving wastage and also insuring a clean and uniformly wound spool or bobbin.

Another object of the invention is to provide apparatus embodying these general characteristic features which will be simple in construction, inexpensive to manufacture and carry on and which shall be efficient in operation.

With these and other objects in view the invention consists in winding thread upon a spool or bobbin, causing said spool to move in a definite direction as the winding operation upon that spool is completed, then moving an empty spool into engagement with the thread and causing said thread to start winding upon said empty spool and breaking the thread between said empty spool and said completely wound spool, completing the winding upon said second spool and then moving the same away and bringing another empty spool into engagement with the thread for the purpose of applying the thread to said last mentioned spool and breaking the thread between said last mentioned spool and the filled spool next adjacent.

The invention consists also in certain novel features of construction and in the arrangement or combination, all of which will be fully described hereinafter and set forth in the appended claims.

In the drawings accompanying and forming part of this application, Fig. 1 is a vertical sectional view, with parts in elevation, through a machine constructed in accordance with my invention; Fig. 2 is a front elevation thereof; Fig. 3 is a vertical sectional view taken on the line 3—3 of Fig. 1; Fig. 4 is a view in elevation showing the development of the cam; and Fig. 5 is a sectional view through one of the empty spools and mounting spindle.

Describing the various parts by reference characters, 1 denotes a suitable base from which rises an upright 2. Journalled in the upper end of upright 2 is a rotating head denoted generally at 3 which is preferably cylindrical in shape and closed at one end by an integral wall 4. A hub 5 projects from the central portion of wall 4 and such hub is reduced in diameter to form a sleeve 6 which projects through a bearing 7 formed on

upright 2. The outer end of sleeve 6 has keyed thereto a sprocket wheel 9 or other suitable driving element, while the opposite end of the rotating head 3 is normally closed by a plate 10 having suitable bearings therein to be referred to hereinafter.

A shaft 12 is journalled in sleeve 6 and also in a bearing 13 formed in plate 10, and the outer end of this shaft is fitted with a pulley 14 or other suitable driving element which is connected by a belt 15 with an electric motor 16 or other source of power. A driving gear 17 is mounted on shaft 12 and is disposed within the hollow rotating head 3. This gear is meshed with a plurality of gears (in the present instance four in number) which are indicated at 18, 19, 20 and 21, each of which is journalled on its respective shaft 22, 23, 24 and 25, such shafts being journalled in suitable bearings formed in end wall 4 and cover plate 10. Each of these shafts 20 is fitted adjacent its outer end with a collar 27 that is retained in position by a set screw 28 and also with a plurality of longitudinally disposed spring fingers 29, while at its inner end each shaft is formed with a clutch member 30. The aforementioned collars 27 prevent longitudinal movement of the shafts, while the spring fingers 29 are adapted each to receive thereon a bobbin or spool 31 on which the thread is adapted to be wound.

Disposed in operative relation to each clutch member 30 is a second or cooperating clutch member 32 which is mounted on a sleeve 33 that is splined to its respective shaft. A coil spring 35 is interposed between each clutch member 32 and a threaded bushing 36 which is screwed into the end of the bearing portion found in the wall 4, such bushing serving to regulate the tension on its respective spring 35 that normally tends to engage the aforementioned clutch members. The outer end of each sleeve 33 is threaded to receive thereon a collar 38 and a lock nut 39, the collars being adjustable on their respective sleeves for a purpose to be referred to hereinafter.

A substantially circular support 40 surrounds the main bearing in upright 2 and this support has bolted thereto a cam plate 41 which is formed with depressed portions 42 and 43 that are adapted to be engaged by the aforementioned collars 38.

In operation, an empty spool or bobbin 45 is placed on the end of the shaft 22 or 23, such spool or bobbin being retained thereon by the aforementioned spring fingers 29. Motor 16 is started which rotates shaft 12 and gears 17, 18, 19, 20 and 21 thereby driving each of the shafts 55

24 and 25, shafts 22 and 23 being disconnected through clutch members 30 and 32. In this connection it will be noted that cam 41 is so shaped that engagement thereof with collars 38 normally 5 retains the clutch members disengaged, and such clutch members engage to drive their respective shafts only when the rotating head 3 has revolved to permit the collars 38 to engage depressed portions 42 or 43. When a collar 38 registers 10 with either of these depressed portions, the appropriate spring 35 moves the sleeve 33 longitudinally to permit the clutch member 32 to engage the clutch member 30, thereby rotating the shaft. The particular periods of rotation of each 15 shaft and spool or bobbin thereon, is indicated by the dot and dash lines 49, 49 and 50, 50 in Figs. 2 and 3. A suitable source of power is also connected to sprocket 9 so as to rotate such sprocket and head 3 a quarter revolution at predetermined time intervals. In Fig. 2 I have 20 shown the manner in which the head 3 may be given a quarter revolution at predetermined time intervals, such means comprising a continuously rotating shaft 51 connected by a Geneva movement to the shaft 52, said movement comprising a crank disk 53 having a pin 54 thereon adapted to enter the slots of a star wheel 55 secured to the shaft 52, the shaft 51 being provided with a locking disk 56 preventing the rotation of the shaft 30 52 while the pin 54 is disengaged from the slots of the said wheel. Power is transmitted from the shafts 51 and 52 to the shaft 12 by means of a sprocket 57, chain 58 and the sprocket 9.

The apparatus is particularly advantageous in 35 connection with the winding of thread or yarn used in the manufacture of rayon. It will be noted that the head 3 completely encloses the gears 17-21, the major portion of the shafts 22-25, the springs 35, and the parts which are 40 liable to be injuriously affected by the vapors arising from the tank in which the thread or yarn is treated. The length of the spindles or shafts 22-25 enables the spools to overhang the tank, thereby permitting convenient access of the 45 threads or yarns to the spools, the tank being located immediately adjacent the base 1, which may extend from a vertical wall of said tank.

As the first empty spool or bobbin reaches its 50 lowermost point of travel, the thread 46 (Fig. 2) having been connected thereto, is wound thereon by the rotary movement of such spool or bobbin as previously described. After a predetermined time the spool or bobbin is wound full or to the desired extent, the rotary head makes one quarter revolution so that the complete spool occupies the position A, Figs. 1 and 2. During such movement of the head however, the spool does not rotate. Meanwhile another empty spool has 55 been placed on the next shaft and this empty spool then moves to the position B (Figs. 1 and 2). Due to the stickiness of the moist thread being wound the empty spool will pick up the thread at this point and wind the same. In case the thread being wound does not possess sufficient adhesive qualities to be picked up by the rotating empty spool, it will be necessary to apply a coating of adhesive to the periphery of the spool. Due to the rotary movement of empty spool B in the direction of arrow 47 and the 60 rotary movement of spool A (by virtue of cam 43) in the direction of arrow 48, the thread will be broken between these two spools and spool B will be wound with thread. As the head moves another quarter revolution, collar 38 rides out 65 of depression 43 and the completed spool or

bobbin stops rotating. This operation continues automatically, the operator merely removing the completed spools and substituting empty spools therefor. It is thus apparent that the winding will continue automatically and the machine can 5 be operated by an unskilled operator.

The construction of the clutch mechanism contributes to the ability of my mechanism to break the thread between the spools in positions A and B, permitting sufficient slippage between 10 the members 30, 32 to enable the spool in position B to wind at least one turn of the thread 46 thereon before the thread between the spools A and B is tensed to its breaking point.

The driving gears for the spools are enclosed 15 in the rotating head which may be filled with lubricant to insure quiet and efficient operation.

It will of course be understood that I have 20 shown and described only one embodiment of my inventive thought which can be carried out in a number of different ways. It will also be understood that the method can be carried out upon one spool or bobbin or simultaneously upon a 25 number of spools or bobbins, the fundamental idea being the winding of the thread upon a spool and transferring the thread to the next spool and then breaking the thread in between the two spools, leaving the completely wound spool and continuing the winding operation upon the next spool. It will also be understood that 30 these operations can be accomplished by turning the head intermittently or there can be a continuous slow movement and furthermore that instead of moving the spools from one position to another the thread could be carried from one 35 spool to another.

Having thus described my invention, what I 40 claim is:

1. Thread winding mechanism comprising a support, a rotatable head journaled on said support, said head being cylindrical with front and back plates forming an enclosure, a plurality of shafts mounted within said head and projecting forwardly and rearwardly therefrom, a shaft 45 extending centrally into and journaled within the said head, a gear on said shaft within said head, a gear on each of the first mentioned shafts also located within said head and meshing each with the gear on the last mentioned shaft, each of the second mentioned gears being provided 50 with clutch mechanism for operatively connecting the same with and disconnecting the same from its shaft, means for detachably connecting a spool to the forward end of each of the first mentioned shafts, means located at the rear of the said head for rendering the clutch mechanism for each of the first mentioned shafts successively operative and inoperative, and means for rotating said shaft with a step by step movement.

2. Thread winding mechanism comprising a 60 rotatable carrier, a pair of shafts projecting from said carrier, means for detachably connecting a spool to each of said shafts, driving means, clutch members for connecting each of said shafts with said driving means, means for imparting a step-by-step movement to the said carrier thereby to move the shafts and the spools thereon to successive stations in the path of travel of said carrier, means located at one of said stations for enabling the clutch members of the shafts 65 moved thereto by said carrier to connect said shafts with said driving means, thereby to rotate said shafts and to initiate the winding of thread upon the spools moved to said station and to substantially fill the said spools with 70 75

thread, and means located at the next station for enabling the clutch members of the shafts moved thereto by the said carrier to connect these shafts with said driving means thereby to continue the rotation of said shafts and the spools thereon and thereby to effect a tension on the thread extending between the spools located at the said stations sufficient to break such thread.

5. Thread winding mechanism comprising a rotatable carrier, a pair of shafts projecting from said carrier, means for detachably connecting a spool to each of said shafts, driving means, clutch members for connecting each of said shafts with said driving means, circumferentially spaced stations to which the said shafts and the spools thereon are moved by the rotation of said carrier, a cam at one of said stations for enabling the clutch members of said shafts to operate, thereby to establish a driving connection between the said driving means and the shafts brought to said station by said carrier, thereby to wind thread upon the spools on the said shafts, means for thereupon moving the said carrier to bring the shafts and the spools thereon to the other station, a cam at said other station for enabling the clutch members of the shafts brought thereto to operate, thereby to establish a driving connection between the last mentioned shafts and the said driving means, thereby to effect further rotation of the shafts and the spools thereon and thereby to effect a tension upon the thread extending between the spools at the two stations sufficient to break the thread.

30. 4. Thread winding mechanism comprising a support, a rotatable hollow head journaled on

said support, a plurality of shafts mounted within said head and projecting forwardly and rearwardly therefrom, a shaft extending into and journaled within the said head and a gear on said shaft within said head, gears on each of the first-mentioned shafts also located within said head and meshing with the gear on the second mentioned shaft, each of the second mentioned gears being provided with clutch mechanism for operatively connecting the same with and disconnecting the same from its shaft, means for detachably connecting a spool to the forward end of each of the first mentioned shafts, circumferentially spaced cams located at the rear of said head and arranged to enable the clutch mechanism for each of the first mentioned shafts to operate to establish a driving connection between each of said shafts successively and the said driving means, thereby to effect the rotation of said shafts by the second mentioned shaft, and means for rotating the second-mentioned shaft with a step-by-step movement, thereby to bring the first mentioned shafts and the spools thereon successively in operative relation to the said stations and the cams located at said stations.

15. 5. In the combination recited in claim 4, means for initiating the winding of the thread upon the spools on each of the first mentioned shafts when brought in operative relation to one of the aforesaid stations, and means for imparting additional rotation to the said shafts and to the spools thereon when brought in operative relation to the next succeeding station.

GEORGE A. WEIMER. 35
